REVERSE FLOW COUNTERCURRENT
CONDENSER

Arnold Werner Baumann, Chicago, Ill.

Application October 8, 1948, Serial No. 53,388

3 Claims. (Cl. 261—114)

1 This invention relates to condensing apparatus, and more particularly to such apparatus of the reverse flow counter-current type, of such construction as to eliminate the need for extra head room above the condenser and at the same time provide a condenser of improved construction and positive and efficient operation.

In counter-current condensers known and in use prior to the present invention there has been provided a vapor inlet near the bottom of the condenser so that the vapor and non-condensable gases flow upwardly toward an outlet near the top while the water flows in counter-current with relation thereto. With this prior conventional design the greater portion of the condenser lies above the vapor inlet which makes it necessary that the ceiling of the operating room be very high in order to house the condenser, or to build a cupola over the condenser itself, which adds materially to the cost of the building for housing the condenser.

In the present invention, I have overcome these disadvantages by providing an improved construction of condenser in which the vapor inlet elbow passes downwardly through the top of the condenser shell, and the inlet vapors are conducted through an inlet tube extending downwardly through the center of the condenser and are released near the bottom of the condenser where they reverse their flow and intersect water curtains and pass upwardly through an improved arrangement of parts, the air and non-condensable gases passing out of the condenser at the top. This eliminates the requirement for extra head room above the vapor inlet elbow, and reduces the cost of building operations or a new building.

The primary object of the present invention is to provide a novel and improved reverse flow counter-current condenser in which no extra head room is required above the vapor inlet elbow, and which reduces the building alteration costs or the cost of a new building.

A further object of the invention is to provide a condenser of the type referred to, in which the incoming vapors are conducted downwardly through the center of the condenser and released near the bottom thereof where they will reverse their flow and pass upwardly through a novel arrangement of water curtains and condenser parts.

A further object is to provide an improved weir construction within the condenser shell and spaced from the inlet vapor tube at a substantial distance above the bottom end of the inlet

tube so as to produce a thin water curtain passing downwardly through an annular space between the inlet tube and the weir supporting wall.

5 A still further object is to provide a deflecting flange extending radially outwardly from the inlet tube near the bottom end thereof, against which flange the water curtain from the weir strikes and from which it is deflected outwardly and falls downwardly to form a further thin water curtain, the incoming vapors passing first through this further curtain, then upwardly and inwardly through the curtain from the weir and up through the annular space between the inlet 10 vapor tube and the weir supporting wall and thence up through the air and non-condensable gases outlet.

Another object is to provide novel heat insulating means around the inlet vapor tube in the space above the weir so that the non-condensable gases and air will not be heated by the hot inlet vapor tube.

20 Further objects, advantages and capabilities, inherently possessed by my invention, will later more fully appear.

The invention is illustrated in a preferred embodiment in the accompanying drawings in which—

25 Fig. 1 is a side elevation of a condenser embodying the present invention.

Fig. 2 is a top plan view of Fig. 1.

Fig. 3 is a vertical longitudinal section of the condenser taken on a median plane.

30 In the embodiment illustrated, the condenser comprises an outer metal shell 1 having a bottom wall 2 and a top wall 3. The bottom wall 2 is preferably conical and connects at its central open bottom end with a water outlet pipe 4 for discharge of the condensing water and condensate. Immediately above the top wall 3 is a vapor inlet elbow 5 having a laterally extending tube 6 adapted to be connected to a vapor inlet supply of steam boiled off from milk in a milk 35 condensing process. Connected with elbow 5 is an inlet tube 7 passing through the central portion of the top 3 and extending downwardly through the center of the interior of the outer shell 1 to a level above the shell bottom 2 a desired distance.

40 Welded or otherwise fixed to the bottom end portion of inlet tube 7, and slightly above the free open end thereof, is a radially extending flange 8 which is preferably of circular perimeter.

45 As will be noted in Fig. 3 the marginal edge of

flange 8 terminates approximately midway between the inlet tube 7 and the shell 1.

Intermediate of the distance between the flange 8 and the top wall 3 the shell 1 is formed with an opening through which extends a water inlet pipe connection 9 connected to any suitable cool water supply. The inner end of water inlet connection 9 is preferably inclined outwardly and downwardly at 10 to provide an overhanging end 11 to downwardly direct the water flowing therethrough so as to promote a smooth level at the top of the body of water a just before it flows over the weir. Secured to the outer end of the pipe connection 9 is a flange 12 having formed therein a circularly arranged series of holes 13 to receive bolts, rivets or the like from a similar flange on the adjacent end of a water supply pipe (not shown). A similar coupling flange 14 is connected to the outer end of inlet tube 6 and having a series of circularly arranged openings 15 to facilitate connection of the elbow 5 with a tube from the milk condensing apparatus (not shown). Tube 6 is preferably slightly inclined downwardly toward the tube 7 so as to facilitate the flow thereto of any condensate that may collect on the walls of tube 6.

Fixed by welding or otherwise as desired to the inner surface of shell 1 in a plane slightly below the bottom of the inlet pipe connection 9 is an annular flange 16 having fixed to its inner edge an upstanding cylindrical wall 17 which at its upper edge is formed with an inwardly extending radial narrow flange 18 constituting an annular weir. As seen in Fig. 3 the inner edge of the weir flange 18 is approximately midway of the radial distance between inlet tube 7 and shell 1, said flange 18 extending annularly around and in spaced relation with the inlet tube 7.

Fixed to the top wall member 3 to extend therefrom is an outlet member 19 serving as an outlet for the air and non-condensable gases being released from the top of the condenser. The outer end of outlet pipe 19 is similarly formed with a coupling flange 20 and holes 21 for connection with an additional outlet pipe (not shown).

Fixed to the outside of the inlet tube 7 by stay studs of the like 22 and spaced outwardly a distance from the inlet tube is a cylindrical steel jacket 23. The space between jacket 23 and inlet tube 7 is filled with any suitable heat insulating material 24 so that the non-condensable gases and air will not be heated by the hot internal vapor tube 7.

The condenser of the present invention preferably operates under a vacuum of about 26½ inches of mercury. In the operation of this condenser condensing water is introduced through the inlet pipe 9 into the annular space above the flange 16 and between the weir vertical wall 17 and the shell 1. This water as indicated at 25 in Fig. 3 accumulates to the level of the top surface of weir flange 18 and slightly higher sufficient to cause such water to flow downwardly in the form of a cylindrical curtain 26. This water curtain will preferably be thin with the water being broken up as it falls and accompanied by more or less spray from the falling water. This curtain of water falls upon the bottom flange 8 where it is deflected laterally outwardly from said flange and then downwardly to form a second thin cylindrical water curtain 27 in which the stream of water is also more or less broken up and accompanied by a greater or less amount of spray from the falling water drops.

The incoming vapors pass downwardly through

tube 7 through the open bottom end thereof and then laterally as shown by the arrows in Fig. 3 and intersect and pass through the water curtain 27 and spray accompanying the same. Some of the condensable portions of the incoming vapors are condensed by the water from curtain 27 and the cooler temperature within the shell.

After passing through curtain 27 the uncondensed portions of the vapors pass upwardly and then inwardly through water curtain 26 where a further amount of the condensable portions of the incoming vapors is condensed, the condensate mixing with the condensing water and flowing downwardly and out therewith through the outlet pipe 4.

After passing inwardly through curtain 26 the uncondensed portions of the vapors continue upwardly through the annular space 28 between the water curtain 26 and the inlet tube 7, some of these vapors being further contacted by the falling water of curtain 26. After passing upwardly beyond the weir 18 the uncondensed portions of the vapors flow around the outside of the insulating jacket 23 and out through the air and non-condensable gases outlet pipe 19.

As will be understood the amount of water flowing inwardly through the water inlet pipe connection 9 will be regulated to produce water curtains of the intensity desired. The coolness of this water will be controlled as desired. As will be seen in Fig. 3 when the water from curtain 27 reaches the bottom wall member 2 of the condenser it will be deflected inwardly and downwardly into the outlet pipe 4, this out-flowing condensing water carrying with it such amount of condensate as will have been picked up thereby during travel of the incoming vapors through the condenser. It will thus be seen that I have provided a reverse flow counter-current condenser requiring no extra head room above the vapor inlet elbow thus reducing building alteration costs or the cost of a new building for housing such condensers.

The foregoing detailed description is given for clearness of understanding only, and no unnecessary limitations should be understood therefrom, for some modifications will be obvious to those skilled in the art.

Having described my invention, I claim:

1. A reverse flow counter-current condenser for eliminating the need for extra head-room, comprising, a vertical cylindrical shell having side walls, a top end wall and a bottom end wall, a vapor inlet tube passing through the top end wall and extending concentrically downwardly in the shell and having an open bottom end spaced upwardly away from said bottom end wall, the diameter of the downwardly extending vapor inlet tube being substantially less than the diameter of the shell to provide a substantial annular space therebetween, a radially and outwardly extending flange fixed to the vapor inlet tube adjacent its bottom open end and of smaller diameter than the shell to leave a space between the perimeter of the flange and the shell, a weir member fixed to the shell and having a bottom and an upstanding wall encircling the vapor inlet tube but spaced a substantial distance radially away therefrom and located approximately mid-way of the vertical portion of the vapor inlet tube, the upper edge of said upstanding wall having a narrow annular flange extending a short distance radially toward the vapor inlet tube but having its inner edge spaced a substantial distance outwardly away from said vapor

inlet tube to form a weir, a water inlet tube connected to an opening in the shell adjacent the bottom of the space behind said upstanding wall of the weir member, said shell having a non-condensable gases and air outlet opening in its upper end portion and a liquid outlet opening in its bottom end well, whereby water passing over said weir will form a curtain encircling the vapor inlet tube but spaced therefrom, which strikes said flange adjacent the bottom end of the vapor inlet tube and passes outwardly and downwardly over the perimeter of this flange to form a second annular curtain, and incoming vapors will pass upwardly from the open bottom end of the vapor tube first outwardly through the second curtain and then at higher elevations inwardly through the first mentioned curtain and out through the non-condensable gases and air outlet opening.

2. A condenser as claimed in claim 1, in which the inner open end of the water inlet tube is inclined outwardly and downwardly to provide an overhanging end to downwardly direct the water

flowing therethrough so as to promote a smooth level at the top of the body of water behind said weir member just before it flows over the weir.

3. A condenser as claimed in claim 1, in which the vapor inlet tube above said weir has fixed to its outer surface a heat insulating jacket so that the outgoing non-condensable gases and air will not be heated by the incoming hot vapors in the vapor inlet tube.

ARNOLD WERNER BAUMANN.
